UNITED STATES PATENT OFFICE.

BERNARD A. GEURINK, OF EAST CLEVELAND, OHIO.

GAS BURNER AND METHOD OF MAKING SAME.

Application filed December 10, 1924. Serial No. 754,887.

This invention, as indicated, relates to a gas burner and method of making the same. More particularly it comprises a casing provided with a slotted top plate, the slots preferably being arranged either transversely or radially. It also includes a top plate formed of two members preferably formed of companion castings, portions of the edges of which when assembled are spaced from each other so as to provide the desired slots. While the invention has been shown and described in connection with a gas burner construction it is to be understood that certain features of the construction are adaptable for use in the manufacture of other articles than gas burners and that it is not intended to limit the scope of the claims through the particular application illustrated.

In gas burners the chief difficulty has been experienced in securing the proper mixture of air and gas so that explosive effects are eliminated when the flame is turned on or turned off. To the accomplishment of the foregoing and related ends, said invention, then, consists of the steps and means herein-after fully described and particularly pointed out in the claims.

The annexed drawings and the following description set forth in detail certain means and one mode of carrying out the invention, such disclosed means and mode illustrating, however, but one of various ways in which the principle of the invention may be used.

In said annexed drawings:—

Fig. 1 is a top plan view of an elongated type of burner embodying the features of the invention; Fig. 2 is a longitudinal sectional view of the construction shown in Fig. 1, taken along the line 2—2 looking in the direction of the arrows; Fig. 3 is a longitudinal sectional view of the top plate taken along the line 3—3 shown in said figure looking in the direction of the arrows; Fig. 4 is a transverse sectional view of the construction shown in Fig. 1 taken along the line 4—4 shown in said figure looking in the direction of the arrows; Fig. 5 is a side elevation of reduced size showing a burner of the type shown in Figs. 1 and 2 mounted upon a tapered mixing arm; Figs. 6 and 7 are top plan views of the respective complementary members which, when assembled, form the top plate of the longitudinal type of burner; Fig. 8 is a top plan view of a circular type of burner embodying the prin-

ciples of the invention; and Fig. 9 is a transverse sectional view taken along the line 9—9 shown in Fig. 8 showing the assembled top plate of the circular type of burner. 60

As shown in Figs. 1, 2 and 5 of the drawings, the invention as applied to a longitudinal type of gas burner embodies a casing 1 provided on its under side with a downwardly tapered portion 2 terminating in a circular aperture 3 surrounded by a shoulder 4 having a flanged outer edge 5. The upper portion of said casing is of rectangular outline and is similarly provided with a shoulder having a flanged outer edge which forms 70 a seat to receive a slotted top plate 6 forming the burner portion of the construction. The casing is adapted to swivelly engage upon the end of a tapered mixing arm 7 having a flared outer end 8. A source of gas supply 9 controlled by a needle valve 10 is positioned centrally of the flared outer end of said mixing arm and the gas and air is thoroughly mixed as it passes through the mixing arm and casing to the slotted orifices of the top 80 plate.

The mixing arm is turned upwardly at right angles at its inner end and is provided with a shoulder 11 and flange 12 adapted to interfit with the complementary structure on the casing, heretofore described, to provide a gas-tight swiveled joint. 85

Upon the under side of said mixing arm adjacent said upturned end, an enlargement or boss 13 is provided, said enlargement 90 having an aperture 14 to receive a bolt 15, the upper end of which extends through the top plate of the burner. A nut 16 on the end of said bolt is adapted to seat against the outer face of said boss 13 and serves to hold said top plate to the casing and to lock the casing in any desired position of angular adjustment about the mixing arm. A second nut 17 may, if desired, be engaged upon the shank of the bolt to hold the companion plate members hereinafter to be described in fixed engagement with each other. A second bolt 18 is provided at the outer end of the casing to hold the top plate to the body portion thereof, the casing being 100 provided with an enlargement or boss 19 about an aperture 20 through which the end of the bolt passes. A nut 21 serves to hold said top plate to said casing and a second nut 22 may be provided to hold the companion top plate members together. In practice it has been found that the use of the 110

second nut upon the shorter bolt will be sufficient to maintain the companion plates in proper registry.

It will be noted that the casing may be swung at any desired angle about the longer of the two bolts just described so as to satisfactorily position the flame jets beneath the object to be heated.

The top plate for the elongated form of burner may be constructed by sawing slots from either side, but such construction is expensive and it is difficult to supply a uniform product for the reason that the saws wear down and break in the course of time and slots of uniform width cannot be regularly supplied. It has therefore been found desirable to form the top plate of two complementary castings 31, 32.

Each of said castings comprise a longitudinal central portion having lateral extensions. The upper of said plate members is shown in Fig. 6 and includes a central section having a reinforcing rib 33 upon the upper side thereof having a series of short lateral ribs 34 reinforcing the lateral extension plates 35. Said extension plates are spaced from each other a distance of less than the standard width of the same and the extensions upon the opposite sides of said central portion are staggered with respect to each other. Bolt holes 38 are provided at points spaced from the ends of said members along the central line thereof and adjacent said bolt holes suitable enlargements 39 project over the intervening spaces for reinforcing purposes. Said end extension plates 36, 37, are made of less width at one end and of greater width on the opposite end in order to properly fit within the rectangular opening of the castings heretofore described. The lower of said plate members 32 is shown in Fig. 7 and comprises an elongated central portion 41 suitably reinforced by a rib on its under side, said rib having lateral extensions 42 reinforcing lateral extension plates 43 which are positioned in staggered relation on the opposite sides of said central portion. Suitable bolt holes 44 are provided, as well as enlargements 45 adjacent said bolt holes and projecting over the intervening spaces between adjacent extension plates.

The lateral extension plates 43 of the bottom member are formed of somewhat less width than the spaces between the lateral extension plates of the top member so that when the top and bottom members of the top plate are assembled laterally extending slots will be provided between the adjacent lateral edges 46 of said respective plate members. The edges at the sides of said holes may be oppositely beveled so as to give to said holes a slight incline from the vertical as viewed from the side, as shown in Fig. 3. By making the lateral ex-

tension plates of the members of different widths the lateral slots on opposite sides of the central portion of the top plate will be staggered with respect to each other. This construction has been found to aid in the thorough mixture of the fuel and air supply of the burner and to prevent miniature explosions when the fuel jets are ignited or extinguished.

As has been indicated, the companion members of the top plate are held in fixed adjustment to each other by means of a nut upon one or both of the securing bolts and the assembled top plate is then held to the casing by means of other nuts or fastening elements secured to the lower ends of said bolts.

In the form of construction illustrated in Figs. 8 and 9, a burner of circular outline, as viewed from above, is provided, said burner comprising a circular casing 51 equipped on its under side with means for attaching the same to a mixing arm similar to that described in connection with the elongated form of construction. A two-part top plate 52 similar to the top plate 6 heretofore described is also provided. The companion sections of said top plate 53, 54, each carry fan-shaped radial extension plates 55, 56, preferably of equal size which, when interfitted, provide radial slots 57 between their adjacent lateral edges. Each of said plate members is provided with an enlarged central portion 61, 62, respectively, from which reinforcing ribs 63, 64, project radially centrally of each of said radial extension plates. Said central enlargements are provided with registering apertures 65, 66, through which a securing bolt 67 is passed. Said bolt is of a length sufficient to secure the circular casing to a mixing arm in the manner illustrated with the other form of construction shown in Fig. 2. A securing nut 68 may be used to hold the two complementary top plate members in adjusted position.

In each of the forms of constructions illustrated it will be noted the slots upon opposite sides of the central portion of the top plate are interrupted by enlargements upon said plate structure. These enlargements will serve to divert the fuel and air mixture to the slotted orifices. The burner has been found to be extremely economical of fuel and is most efficient in operation. The parts are few in number and may be readily assembled or easily disassembled for purposes of adjustment and repair.

Other forms may be employed embodying the features of my invention instead of the one here explained, change being made in the form or construction, provided the elements stated by any of the following claims or the equivalent of such stated elements be employed, whether produced by my pre-

ferred method or by others embodying steps equivalent to those stated in the following claims.

I therefore particularly point out and distinctly claim as my invention:—

1. A gas burner comprising an elongated casing open at its upper side, a pair of interfitting members forming a top plate for closing said casing, a rib extending longitudinally of each of said members, a series of lateral extensions on each side of said longitudinal ribs, means for securing said members to each other so as to provide laterally extending orifices on each side of said top plate in staggered relation to the orifices on the opposite side, and means for supplying a fuel mixture through said casing to said orifices.
2. A gas burner comprising an elongated casing open at its upper side, a pair of interfitting members forming a top plate for closing said casing, a rib extending longitudinally of each of said members, a series of lateral extensions on each side of said longitudinal ribs, means for securing said members to each other so as to provide laterally extending orifices on each side of said top plate in staggered relation to the orifices on the opposite side, reinforcing ribs extending from said central rib over each of said lateral extensions, and means for supplying a fuel mixture through said casing to said orifices.

Signed by me this 10th day of November, 1924.

BERNARD A. GEURINK.
